[57] CLAIM

The ornamental design for a worktable or similar article, substantially as shown and described.

DESCRIPTION

FIG. 1 is a perspective view of one embodiment of the worktable or similar article;

FIG. 2 is a side view of the worktable or similar article shown in FIG. 1; and

FIG. 3 is a front view of the worktable or similar article shown in FIG. 1.

The side of the worktable not shown is a mirror image of the side shown in FIG. 2.

FIG -1

FIG -2
